METALLIC ROPE

John W. Gottschalk, Philadelphia, Pa.

Application July 31, 1931, Serial No. 554,370

1 Claim. (Cl. 117—52)

There has been on the market for some time a cleaning and abrading material which is formed from a single strand of wire which is passed between rolls to flatten it through a coiling mechanism and therefrom through a set of feeding rolls so that during the travel of the wire there is imparted to it an inherent tendency to curl. This coiled wire is tangled into a bunch and used as an abrading or cleaner.

10 There are many lines of manufacture in which material of this character can be advantageously employed and I have devised from this material a novel metallic rope in which the strands are in the shape of coils which are retained in close 15 relation either by the twist imparted to the strands during the formation of the rope so that juxtaposed coils interlock, or by securing in any desired manner the various strands in closely juxtaposed relationship, for example, by means of 20 a strand of material wound around the coils.

In some cases instead of each coil strand having a hollow center it may be formed around a core of any desired character.

25 With the above and other objects in view, as will hereinafter more clearly appear, my invention comprehends a novel metallic rope and a novel method of making it.

It further comprehends a novel metallic rope 30 wherein the strands thereof consist of coiled strips which are retained throughout their length in close relationship with juxtaposed strips.

It further comprehends a novel metallic rope 35 made up of coiled strands in which any desired number of the coiled strands may be formed around a core.

It further comprehends a novel method of making a metallic rope.

Other novel features of construction and advantage will hereinafter clearly appear in the detailed description and the appended claim.

For the purpose of illustrating the invention, I have shown in the accompanying drawing typical embodiments of it, which, in practice, will 45 give satisfactory and reliable results. It is, however, to be understood that the various instrumentalities of which my invention consists can be variously arranged and organized, and my invention is not limited to the exact arrangement 50 and organization of these instrumentalities as herein set forth.

Figure 1 is a side elevation of a metallic rope embodying my invention.

Figure 2 is also a side elevation of a metallic 55 rope embodying my invention, the strands being

retained in closely juxtaposed relationship by means of a binder.

Figure 3 is a side elevation of another embodiment of my invention wherein the different strands are provided with cores.

Figure 4 is a perspective view illustrating diagrammatically one manner in which my novel metallic rope can be manufactured.

Figure 5 is a side elevation of another embodiment of my invention in which the coils are substantially straight and interlock with each other.

Figure 6 is a side elevation of another embodiment of my invention in which the coils are straight but a binding member is employed.

Figure 7 is a detail of another embodiment of my invention.

Similar numerals of reference indicate corresponding parts.

Referring to the drawing:

Referring first to the embodiment seen in Figure 1, I have shown in this figure a metallic rope 1 embodying my invention and consisting of coiled strands 2, the different coiled strands having a twist imparted to them in the manufacture so that juxtaposed coils interlock with each other 30 and retain the rope in assembled condition.

In the embodiment seen in Figure 2, the metallic rope 3 has its strands of the same formation but they are retained in rope formation by means of a binding strand 4 preferably a wire.

In the form seen in Figure 3 the different strands 5 are formed around a core 6. This core may be of a metallic, fibrous or textile nature, or, in fact, may be of any desired material. In carrying out my invention different strands of material 7, such as, for example, wire, are placed on the bobbins or spools 8. Any desired number of strands may be employed but I have deemed it only essential, for purpose of illustration, to show three strands. These strands pass by a guide 9 and between forming rolls 10 and 11 which may be simply feed rolls or which, if desired, may have a forming action on the wires so as to vary their shape in cross section. The wires pass from the rolls 10 and 11 around the curling mechanism 12 and 13 consisting of offset rods and therefrom between the tensioning rolls 14 and 15 so that the different strands have imparted to them an inherent tendency to curl while under tension and during their continuous feed.

The passing of the strand over a 100 curling edge while under tension causes the metal at one side of the metal strand to be stretched thereby imparting to the strand an inherent tendency to form a helical coil. The coiled strands 16 passing from the tension rolls 14 and 15 are 110

twisted together into a metallic rope 17 which is received on the bobbin 18. This bobbin 18 is adapted to revolve on its axis and also to be bodily revolved so that the rope formation is produced as shown in Figures 1, 2 and 3. The bobbin 18 is mounted in a bracket 19. The gear 20 drives a gear 21 and is mounted on a shaft 22 and for convenience of illustration the shaft 22 is shown as provided with a pulley 23 thereby adapting it to be driven by any desired source of power. The shaft 22 is journalled in the bracket 19 and provided with a gear 24 which meshes with a gear 25 fixed to the spindle 26 of the bobbin 18. It will thus be clear that as the spindle 26 revolves on its axis the bobbin is also bodily revolved so that a finished rope appears as shown in Figure 1.

The binding wire 4, if employed, may be wound around the rope during its manufacture or afterwards, as may be desired.

20 In case a core is employed the wire may be formed around the core.

In the embodiment of my invention seen in Figure 5 instead of the separate coiled strands being twisted into rope formation they are substantially straight and consists of the strands 27, 25 the juxtaposed coils of which interlock with each other.

30 In the embodiment seen in Figure 6 the construction is the same as that seen in Figure 5 except that in addition I employ a binding member 28, such as, for example, a wire which is wound around the assembled coiled strands and in this case it is not necessary that juxtaposed coils interlock with each other to maintain the formation 35 of the rope.

40 In Figure 7 I have shown another embodiment of my invention wherein the coiled strands 29 are wound around a core in the form a helix 30. This helix, as illustrated, is in the form of a helically wound flat band but the shape of the band in cross section is immaterial. This embodiment of my invention seen in Figure 7 is of special advantage in cases wherein a smaller amount of the coiled strands is necessary and still provide a rope 45 of a given diameter.

I have found in practice that a metallic rope of this character has a very wide application in

the arts, for example, it may be very advantageously employed as a filter for filtering liquids or gases. It can also be employed very advantageously in various types of padding and upholstery so that the proper resistance and resiliency is obtained. When rope of this character is employed, for example in upholstery padding and the like, inherent resiliency of the coils causes the rope to always return to its initial or normal formation after the pressure to which it has been subjected is relieved.

80 If it is desired to have the coils of juxtaposed coiled strands interlock this can be accomplished by passing the assembled coiled strands through an opening, the walls of which converge towards the discharge end, such as, for example, a funnel so that the coiled strands will be compressed together and the individual juxtaposed coils will interlock with each other.

90 Where a wire is employed to maintain the assembled coiled strands, it can be applied during the assembly of the strands or after the strands have been assembled in rope or other formation as may be desired.

95 It will now be apparent that I have devised a new and useful metallic rope and method of making it which embodies the features of advantage enumerated as desirable in the statement of the invention and the above description, and while I have, in the present instance, shown and described preferred embodiments thereof which will give in practice satisfactory and reliable results, it is to be understood that these embodiments are susceptible of modification in various particulars without departing from the spirit or 100 scope of the invention or sacrificing any of its advantages.

105 Having thus described my invention what I claim as new and desire to secure by Letters Patent, is:

110 The herein described metallic rope consisting of metal strands each having the strand at one side stretched to cause the strands to have an inherent tendency to form helical coils said strands being arranged longitudinal side by side and having the coils of juxtaposed strands interlocked.
